APPARATUS FOR MANUFACTURING LONG
FIBRE INTO YARN

Samuel E. Thomas and Walter R. Guthrie, Allentown, Pa., assignors to Lehigh Spinning Company, Allentown, Pa., a corporation of Pennsylvania

Application October 25, 1944, Serial No. 560,262

7 Claims. (Cl. 19—158)

1

This invention relates to apparatus for manufacturing long fibre into yarn and is a continuation in part of our earlier file case Serial No. 359,126, filed September 30, 1940.

Fibres for manufacturing yarns have many classifications. There are the vegetable, animal, and artificial fibres, which may be subdivided into long and short fibres. Another classification presented in a survey by Charles Richard Dodge, at page 31, of "Useful Fibre Plants of the World" of the U. S. Department of Agriculture, published by the Government Printing Office in 1907, reveals that fibres adapted for spinning may be divided into fabric, netting, and cordage fibres. Cordage fibres are rarely used in weaving and netting because they are a hard fibre, and they are also long fibres. The apparatus of the present invention has particular application to the manufacture of a yarn from long vegetable fibre. It also has particular application to any long artificial fibres such as synthetic cellulose fibres prepared by the viscose, acetate, cuprammonium, nitrocellulose, and other processes, the product being known as "rayon"; or the artificial fibres of cellulose xanthate, known as "Cellophane"; or the artificial fibres from the relatively new protein-like polyamides known as "nylon." Flax, ramie, jute, etc., are examples of the long, soft, vegetable fibre, while coir and manila, sisal, and common hemp are examples of long, hard, vegetable cordage fibre referred to herein.

One of the objects of the present invention resides in a simplified apparatus for use in the manufacture of long fibre, both hard and soft, into yarn. The initial step in the manufacture of the yarn is performed on the Good's principle, well known in the art, and which step is practiced by a combined combing and stretching or straightening machine of Good disclosed in U. S. Patent 94,462 of October 5, 1869. In the machine revealed in the aforesaid patent, the resulting sliver was of uneven weight, and no provision was made for delivering it in a unit for subsequent treatment. The advantage of the present invention includes collecting the fibre under pressure in a continuous layer, such as a roll, in relatively large compact units adapted for treatment in subsequent operations in transforming the units into yarn. The initial step hitherto unknown in the industry will process the long soft fibre in a manner that has many advantages over regulation methods, among which are:

When applied to the manufacture of yarns for cordage, where the long hard fibre is used, the present invention has the advantage over

2

current practice, in that the softening emulsion permeates the mass of raw material because of the pressure applied when the sliver is collected into large compact units; the large compact units of the intermediate material may be handled and stored economically in the minimum of factory floor space; and the compact unit does not become ravelled and roughened in handling and will not break and slough so readily in subsequent operations.

Among the objects of the present invention is the creation of an apparatus which permits the long fibre, both hard and soft, to be collected in a compact unit, such as a roll, under pressure, and to feed the fibre directly from the compact units to machines that perform certain subsequent steps in the method of treatment.

Heretofore in forming rolls with apparatus of the prior art, only slight pressure was used in the formation of the roll and should a substantial pressure be used in order to place more material in a roll of a given size, it was necessary to use a separator strip between the laps in order that the laps could be unwound without tangling.

In the present device the fibre of each lap is wound onto the roll under extreme pressure far exceeding anything heretofore known in the art which makes it possible to place in one roll of approximately five feet in diameter and six inches in thickness, two to three hundred pounds of fibre.

The apparatus of the present invention places the laps upon the roll in a manner in which the fibres are free of tension while under considerable pressure, thus enabling the laps to be unwound in succeeding operations uniformly and without substantial entanglement with the fibres of the adjacent lap. It is accordingly among the purposes of the present invention to provide an apparatus to form rolls of fibre in which each lap as it is placed upon the roll is under substantial pressure and the fibres making up the lap are free of longitudinal tension.

With the foregoing objects in view, the invention consists of a novel combination of apparatus capable of carrying to accomplishment the foregoing objects but it is to be understood that the invention is not to be limited to its scope beyond the claims subjoined, inasmuch as the disclosure reveals only the preferred embodiment of the invention.

In the drawings, wherein the preferred embodiment of the invention is illustrated:

Figure 1 is a side elevation in the nature of a diagram showing the precision feeding device, 55 coupled with the Good's machine combining the

combing and spreading action, and a roll former coupled with the combined comber and spreader, which mechanism is the initial step in the treatment of both the hard and soft, long fibre.

Figure 2 is a top plan view of the delivery end of the combined comber and spreader.

Figure 3 is a side elevation of Figure 2.

Figure 4 is a perspective view of the ram and actuating cables removed from the cylinder and the combined comber and spreader, whereby the tension on the rolls is applied.

It will be understood that the apparatus illustrated in the drawings, from Figure 1 to Figure 4, inclusive illustrates apparatus used in the manufacture of yarn from long soft fibre such as flax, ramie, jute, etc., where the heads of raw-stock, run from 2 to 12 feet long. The extremely vigorous combing action, together with the spreading, or drawing action, and the stretching and straightening action performed by the Good's machine of the character revealed in the Patent 95,462, is not followed primarily to break the fibre into shorter lengths. Although the machine does split some of the fibre in the direction of its length, and also does break the fibre into shorter lengths to some extent, the major portion of the breaking into shorter lengths is preferred to be accomplished in the breaker card, and in the case of the soft fibre, the ideal condition sought is to reduce the breaking into shorter lengths to a minimum in the Good's machine, and do all of the breaking in a breaker card.

Referring to the drawings where the apparatus is disclosed, an operator breaks the bales 20 of raw fibre and loads the loose fibres in parallel relation on a wheeled barrow, or box 21, from where the box is moved onto the platform 22 of the weighing register of the precision feeding device, indicated generally at A. In order to obtain a desired weight in the finished yarn, it is one of the essential features of the present invention to control and regulate the feeding of the raw stock to the Good's machine, indicated generally at B. To accomplish this purpose, the operator is provided with a precision feeding device which eliminates the feeding of the machine B, by the skill of the operator alone, based on his experience developed by long periods of trial and error, commonly referred to as a rule of thumb.

A register supported on stand 51 is initially selected to provide the necessary weighing facilities required for the present invention the register constituting the subject matter of our co-pending application Serial No. 557,446, filed October 6, 1944. In the present instance, the design may utilize anything less than one complete circumference of the dial 52. The weight indicating hand 54 cooperates with the dial to register the actual weight of the fibre in the wheeled box 21 on weighing platform 22, after the tare beam is set to counterbalance the weight of the empty box in the customary manner well known in the industry. An indicating hand 60 which is disposed to overhang the margin of dial 52 adjacent the scale markings follows a path conforming to the weight indicating hand 54 when it is coupled to move with the motion of the feed table 25.

When a box 21 of raw fibre is placed on platform 22, and the weight-indicating hand 54 moves to the position on scale markings commensurate with the actual weight of the contained fibre, after the tare has been deducted by the usual manipulation of tare beam, then the 75

feed table speed-indicating hand 60 is moved, as previously described, to a position coinciding with the position of hand 54. As hand 60 moves counterclockwise being driven by means 40-47 inclusive upon operation of table 25, the operator removes raw fibre from the box 21 and supplies it to the feed table 25, so as to keep the weight-indicating hand 54, moving in response to the loss of weight in box 21, in substantial alignment with the movement of the speed-indicating hand 60. It will therefore, be seen that the method of treating fibre herein, utilizes a regulated amount of fibre at a certain stage, preferably at the initial step where the fibre is fed to the Good's machine B, through the instrumentality of the precision feeding device as described in the foregoing.

In addition to the feed table 25, the machine B is equipped with a pair of spring loaded fluted feed rolls 69 and 70, whereby adequate pressure may be applied. It is pointed out that there is no crushing or breaking pressure applied to the traveling fibre by the feed rolls 69, 70, the pressure being adjusted to a tension only necessary to grip the ends of the fibres and pull them free of the feed table 25, and pass them into contact with the slow combing chain 75 of the machine B.

As distinguished from the customary preliminary crushing and opening of the fibre, it will be seen that this invention applies a combination combing, spreading or drawing, stretchings, and parallelizing action where all tension is administered in a direction of the axis of the fibre. This step is accomplished by the slow combing chain 75 operating on the traveling fibre in conjunction with the fast combing chain 76. These chains not only comb, draw and stretch the traveling fibre but simultaneously align all the fibre in parallel relation with respect to the axis of the fibre on the Good's principle in Patent 95,462. The speed of the slow combing chain 75 is such as to move faster than the peripheral speed of the feed rolls 69, 70 and consequently there is a drawing, stretching, combing and parallelizing action on the fibre between the slow combing chain 75 and the feed rolls. The fast combing chain 76 moves in the same plane and in the same direction as the slow chain 75, but it moves at a rate of speed ten times faster than the slow chain. The combing is then performed in a horizontal plane different from tangential combing and breaking on the cylinder of a breaker card. To facilitate adherence of the fibre to the combing pins, to be presently described, on the slow combing chain 75, a pair of lantern rolls 78, are provided, one near one end of the chain, and the other at the opposite end. Each of these rolls consist of a plurality of spaced bars 79, which are arranged to revolve with the roll and press the fibre downwardly between the combing pins and hold the fibre securely to the slow chain 75, so that greater combing and stretching action ensues when the fast chain 76 pulls the fibre free of the slow chain.

While the fibre is passing along the slow chain 75, a regulation softening emulsion 80 is sprayed in a fine mist by a spray head 81 connected to a supply tank having a suitable pressure applied, not shown, by means of the pipe 82.

The slow combing chain 75 consists of a pair of endless chains trained over sprockets 83, 84, on shafts that are journaled in the side frames. The fast combing chain 76 is constructed like the slow chain 75 and its pair of chains are

trained over sprockets 85, 86 likewise mounted on shafts journaled in the side frames.

The slow chain 75 and fast chain 76 having cross bars 88 move in a direction from right to left in Figure 1, of the drawings. As the fibre is fed by the feed rollers 69, 70 to the slow moving chain 75, it is carried forward by the slow chain to the path of the combing or hackle pins 89 on the fast chain 76, where these pins comb through the forward ends of the fibre in a stretching action until sufficient of the fibre is being clawed and combed to pull it free of the pins 89 on the slow moving chain 75, whereupon the fibre is carried by the fast chain 76 to the delivery rolls 90, 91, which strip the fibre free of the hackle pins on fast chain 76. The fibre then passes from the set of delivery rolls 90, 91 into a lateral condensing trough 92, which progressively narrows the width of the web of fibre, and has a tendency to thicken the web.

The fibre then passes through the first set of condensing rolls 93, 94 where the thickness of the web is reduced. After passing through rolls 93, 94 the web of fibre is again laterally reduced as it passes through condensing trough 95, and its thickness is then reduced by the second set of condensing rolls 96, 97 from where the web emerges as a sliver, which is unmatted and unfelted by any extraneous means except for the cohesion produced in the two stages of lateral and vertical compressing, or condensing, above described. From the second set of condensing rolls 96, 97, the web now reduced to a sliver, is fed to the roll former, indicated generally at C, which is combined in a novel manner with the delivery mechanism of the machine B.

The mechanical features of the roll former C, consist of a support composed of a pair of side frames consisting of plates 100, 101 secured to the floor. The support further consists of a pair of inverted U-shaped frames 102, 103 rearward of the frames 100, 101, and in these latter frames are journaled the shafts 104, 105 which drive the traction supplying rolls 106, 107 respectively, that wind the sliver on the core, as will presently appear. Although the support is shown and described as two pairs of frames, one pair 100, 101 for rotatably supporting the core, and the other 102, 103, for supporting the shafts, it is within the contemplation of the invention to combine the functions and use by a single pair of frames such as a continuation of the side frames 23, 24 of the machine B.

Opening at the upper edge, and extending vertically to the approximate centers of the side frames 100, 101 are aligned slots, one in each frame, which form guideways 108 that receive portions adjacent the ends of a spindle 109 that supports a wooden core 110 on which the sliver of fibre is wound. The driving rolls are arranged to provide a space between the upper segments of their peripheries which forms a cradle 111 that initially supports the core 110, and the roll 112 of sliver as the roll is wound on the core. It is to be noted that the outer periphery 110a of the core 110 is tapered slightly so the core may be easily removed from the roll when the core is struck with a hammer.

In order to provide for mounting and demounting the rolls of sliver 112, there are a pair of flat connector plates 118, one on each side, formed with a banjo slot 119 to receive the heads 109a on the spindle 109. At the lower part, each connector plate has a stud 120 with which the loops 121 on the end of the pair of pressure-applying

cables 122 engage. The pair of cables 122 are trained about pulleys 123, 124 mounted conveniently on the machine, and are secured, one to each end of a cross piece 125 on the end of an air ram 126.

The ram is connected to the piston 127 which operates in an air cylinder 128 mounted under machine B. The air ram 126 supplies a constant pressure usually 60 lbs. which acts as a compression force on the roll of sliver 112, as it is wound on the core 110. This pressure is supplied from an air reservoir 130, maintained under the desired pressure, through a pipe 131 which connects with the control valve 132, having a rotary core 133, operated by a handle, not shown, with a passage 134, which, when in the position shown in Figure 3, connects pipe 135 with the opposite end of cylinder 128 by pipe 136, where the pressure is relieved through an opening 137 in the cylinder head. With the pressure on the ram released, cables 122 are slack, then the connector plates 118 may be lifted free of the spindle 109, and a crane may be used to lift the wound pressure compacted roll out of the frames 100, 101, and an empty core is placed in the cradle 111 with a new spindle 109 inserted therein. Then the connector plates, and the cables, are assembled ready to wind another roll of sliver.

The rolls 112 are wound on the core under the pressure transmitted through the cables 122 from the ram 126 pulling downwardly on the connector plates 118, and this maintains the periphery of the increasing roll of sliver in contact with the peripheries of rolls 106 and 107. The rolls 106, 107 are driven by chain and sprocket connection 140, shaft 104, 105, chain and sprocket connection 141, with shaft 142 of the lower condenser roll 94, thence by chain and sprocket connection 143, to the main drive shaft 144, which carries the pulley 145 and idle pulley 145a that are connected by a shiftable belt to the prime mover, not shown. The drive for the condenser rolls 96, 97, is taken from chain 141 by a sprocket on shaft 150b which carries lower roll 97. The drive for upper roll 96 is taken from shaft 150b, gears 150, 149 to idle shaft 146, thence by chain and sprocket connections 147 to shaft 148 which carries roll 96. The lower roll 91 only, of the delivery rolls 90, 91 is driven by the main shaft 144, the upper roll 90 being spring-pressed against the lower roll like shown and described in connection with the feed rolls 69, 70.

Sliver formed on apparatus of this type is unusually heavy for example in one operation in which jute fibre is being formed into rolls the sliver directed to the roll former weighs approximately 70 pounds per hundred yards. When sliver of this type is formed into a roll, especially under extreme pressure as in the present case, where the peripheral speed of the roll is the same or greater than the longitudinal speed of the slivers from the delivery rolls 90, 91 and condenser rolls 96, 97, the roll formed under such conditions is irregular and difficult to use in subsequent operations as the fibre of adjacent laps become entangled and the laps cannot be unwound uniformly.

To obtain a uniform roll having substantially straight sides from which the laps can be easily

removed in succeeding operations, it has been discovered that a plus feed to the roll former sufficient to permit the application of pressure to the roll without longitudinal tension in the fibres of the lap is required. Usually this plus feed amounts to about 2% although with certain fibres satisfactory results may be obtained within a range of 2% to 8%. The drive for rolls 106, 107 is so arranged in a suitable manner as to give these rolls a slower peripheral speed than the longitudinal speed of the advancing sliver sufficient to wave or crimp the sliver as it forms upon the roll, thus permitting the fibres of the lap being formed to seek their position without longitudinal tension.

Only the long soft fibre is treated in a conditioning room and subjected to a breaker card. As the compacted units, such as the rolls 112, are removed from the roll former C containing the softening emulsion 80 they are confined in a closed chamber, or conditioning room, at atmospheric pressure. The temperature in the room is kept at no less than room temperature, and preferably ranging from 85 to 100 degrees Fahrenheit, and at a humidity less than the saturation point. The relative humidity is maintained within the range of from 80 to 90 in the conditioning chamber. The rolls of long soft fibre are preferably placed upright and subjected to this conditioning treatment for a period of from 12 to 24 hours, at which time the rolls are removed and are ready for further processing.

After long hard fibre has been subjected to the combing, drawing or spreading, stretching, and straightening operations and has been formed under pressure of 60 lbs. into rolls 112, instead of conditioning the hard fibre, it is conveyed on a suitable vehicle to a creel combined with the breaker card not shown.

We claim:

1. A roll former comprising a frame having guide slots therein, a core positioned within the frame upon which a continuous sliver may be wound, a spindle for the core having its ends extending through the guide slots of the frame, whereby the core is movable longitudinally with respect to said slots, a pair of traction rolls rotatably supporting the core, means for rotating the traction rolls so that upon operation thereof the core is rotated to wind sliver thereon, said guide slots extending in such direction that movement of the core in one direction longitudinally with respect to the slots causes it to move towards the traction rolls, a pair of plates, means for detachably securing the end portions of said spindle to said plates, flexible cables secured at one end to said plates, a fluid operated ram for applying a substantially constant tensile force to the other end of said cables in a direction tending to move the core in said slots in a direction towards the traction rolls so that a substantially uniform pressure is applied to the sliver as it is wound on the core.

2. In an apparatus for treating fibre having means for forming fibre onto rolls including delivery rolls and means for driving the same for advancing a continuous sliver of long fibres; the improvement which comprises a core upon which the sliver may be wound to form a roll, a frame having sidewalls, said frame being constructed and arranged to so guide the sliver to the core that the sliver is wound spirally upon the core between said sidewalls, traction applying rolls rotatably supporting the core and sliver wound thereon, means for applying a compressible force to the sliver being wound on the core, and means

for driving the traction rolls at a peripheral speed of less than the linear speed of the sliver as fed to the traction rolls by said delivery rolls whereby upon rotation of the traction rolls a transversely crimped lap not under tension is wound upon the core to form a roll which readily may be unwound.

3. In an apparatus for treating fibre having means for forming fibre onto rolls including delivery rolls and means for driving the same for advancing a continuous sliver of long fibres; the improvement which comprises a core upon which the sliver may be wound to form a roll, a frame having sidewalls, said frame being constructed and arranged to so guide the sliver to the core that the sliver is wound spirally upon the core between said sidewalls, traction applying rolls rotatably supporting the core and sliver wound thereon, means for applying a compressible force to the sliver being wound on the core, and means for driving the traction rolls at a peripheral speed 2-8% less than the linear speed of the sliver as fed to the traction rolls by said delivery rolls whereby upon rotation of the traction rolls a transversely crimped lap not under tension is wound upon the core to form a roll which readily may be unwound.

4. In an apparatus for treating fibre having means for forming fibre into rolls including delivery rolls and means for driving the same for advancing a continuous sliver of long fibers; the improvement which comprises a frame having guide slots therein, a core positioned within the frame upon which continuous sliver may be wound, a spindle for the core having its ends extending through the guide slots of the frame, whereby the core is movable longitudinally with respect to said slots, traction applying rolls rotatably supporting the core and sliver wound thereon, means detachably connected to the ends of the spindle for applying a compressible force to the sliver being wound on the core and means for driving the traction rolls at a peripheral speed less than the linear speed of the sliver as fed to the traction rolls by said delivery rolls whereby upon rotation of the traction rolls a transversely crimped lap not under tension is wound upon the core to form a roll which readily may be unwound.

5. In an apparatus for treating fibre having means for forming fibre into rolls including delivery rolls and means for driving the same for advancing a continuous sliver of long jute fibres; the improvement which comprises a frame having guide slots therein, a core positioned within the frame upon which a continuous sliver may be wound, a spindle for the core having its ends extending through the guide slots of the frame, whereby the core is movable longitudinally with respect to the slots, traction applying rolls rotatably supporting the core and sliver wound thereon, means for driving the traction rolls at a peripheral speed less than the linear speed of the sliver as fed to the traction rolls by said delivery rolls whereby upon rotation of the traction rolls a transversely crimped lap not under tension is wound upon the core to form a roll which readily may be unwound, a pair of plates, means for detachably securing the end portions of said spindle to said plates, a flexible cable secured at one end to each of said plates, and a fluid operated ram for applying a substantially constant tensile force to the other end of said cables in a direction tending to move the core

in said slots in a direction towards the traction rolls.

6. In an apparatus for treating fibre having means for forming fibre into rolls including delivery rolls and means for driving the same for advancing a continuous sliver of long jute fibres; the improvement which comprises a frame having guide slots therein, a core positioned within the frame upon which a continuous sliver may be wound, a spindle for the core having its ends extending through the guide slots of the frame, whereby the core is movable longitudinally with respect to the slots, traction applying rolls rotatably supporting the core and sliver wound thereon, means for driving the traction rolls at a peripheral speed 2-8% less than the linear speed of the sliver as fed to the traction rolls by said delivery rolls whereby upon rotation of the traction rolls a transversely crimped lap not under tension is wound upon the core to form a roll which readily may be unwound, a pair of plates, means for detachably securing the end portions of said spindle to said plates, a flexible cable secured at one end to each of said plates, a fluid operated ram for applying a substantially constant tensile force to the other end of said cables in a direction tending to move the core in said slots in a direction towards traction rolls, and means for operating the ram to a position to slacken the cables in order to quickly detach the plates and remove a full roll of sliver and supply an empty core in preparation for forming a succeeding roll.

7. In an apparatus for treating fibre having means for forming fibre into rolls including delivery rolls and means for driving the same for advancing a continuous sliver of long jute fibres; the improvement which comprises a frame having guide slots therein, a core positioned within the frame upon which a continuous sliver may be 40

wound, a spindle for the core having its ends extending through the guide slots of the frame, whereby the core is movable longitudinally with respect to the slots, traction applying rolls rotatably supporting the core and sliver wound thereon, means for driving the traction rolls at a peripheral speed 2-8% less than the linear speed of the sliver as fed to the traction rolls by said delivery rolls whereby upon rotation of the traction rolls a transversely crimped lap not under tension is wound upon the core to form a roll which readily may be unwound, a pair of plates, means for detachably securing the end portions of said spindle to said plates, a flexible cable secured at one end to each of said plates, and a fluid operated ram for applying a substantially constant tensile force to the other end of said cables in a direction tending to move the core in said slots in a direction towards the traction rolls.
